OF

O 11,726

EX

No. 11,726

April 13, 1880

UNITED STATES PATENT OFFICE.

JOHN GRIMSHAW, OF PATERSON, NEW JERSEY.

DESIGN FOR A HANDKERCHIEF.

SPECIFICATION forming part of Design No. 11,726, dated April 13, 1880.

Application filed February 7, 1880. Term of patent 3½ years.

To all whom it may concern:

Be it known that I, JOHN GRIMSHAW, of Paterson, in the county of Passaic and State of New Jersey, have invented a new and original Design for a Handkerchief, of which the following is a specification.

This invention relates, first, to the new ornamentation of the body of a handkerchief, and, second, to the new ornamentation of the border for the same.

The accompanying photograph illustrates my new design.

The body A of the handkerchief contains squares or checks a b, composed of parallel lines. Squares or checks a are light, and b are dark.

Two opposite sides, B B, of the border contain parallel stripes prolonged from the stripes in checks b, so that checks b and borders B B are alike, while the borders C C are plain.

I claim—

1. The design for the body of a handker-

chief, which consists of the light and dark checks a b, formed of parallel stripes, substantially as described, and shown in the accompanying illustration.

2. The design for the border of a handkerchief, which consists of the opposite striped border, B B, formed by the prolongation of the stripes from checks b, and the opposite plain borders C C, substantially as described, and shown in the accompanying illustration.

3. The design for a handkerchief, which consists of the body A, formed of checks or squares a b, composed of different shades of parallel stripes, the borders B B, composed of stripes prolonged from the checks b, and the plain borders C C, substantially as described, and shown in the accompanying illustration.

JOHN GRIMSHAW.
